DECORATIVE PADDLE

Bruce Carlton, Memphis, Tenn.
(Rte. 5, Box 548-R, Hot Springs, Ark. 71901)

Filed Dec. 20, 1967, Ser. No. 9,863

Term of patent 7 years

U.S. Cl. D34—5
Int. Cl. D21—03

FIG. 1 is a perspective view of a decorative paddle showing my new design.

FIG. 2 is a sectional view thereof taken as on the line II—II of FIG. 1.

The undisclosed side of the decorative paddle is the same as the disclosed side.

I claim:

The ornamental design for a decorative paddle, as shown and described.
